US0D1004980S

(12) **United States Design Patent** (10) Patent No.: **US D1,004,980 S**
(45) Date of Patent: ** Nov. 21, 2023

(54) **ORAL CARE IMPLEMENT**

(71) Applicant: **Colgate-Palmolive Company**, New York, NY (US)

(72) Inventors: **Eduardo Jimenez**, Manalapan, NJ (US); **Kenneth Waguespack**, North Brunswick, NJ (US); **Robert Moskovich**, Manakin-Sabot, VA (US); **Roger Kirchhofer**, Lucerne (CH); **Kurt Bieri**, Lucerne (CH); **Joachim Storz**, Zell am See (AT); **Andreas Wechsler**, Zell am See (AT)

(73) Assignee: **Colgate-Palmolive Company**, New York, NY (US)

(**) Term: **15 Years**

(21) Appl. No.: **29/731,288**

(22) Filed: **Apr. 14, 2020**

Related U.S. Application Data

(62) Division of application No. 29/591,230, filed on Jan. 18, 2017, now Pat. No. Des. 883,676, which is a division of application No. 29/512,833, filed on Dec. 23, 2014, now Pat. No. Des. 780,457.
